DESIGN FOR A LOCKING DEVICE

Harry F. George, Chicago, Ill.

Application February 5, 1942, Serial No. 105,648

Term of patent 3½ years

To all whom it may concern:

Be it known that I, Harry F. George, a citizen of the United States, residing at Chicago, in the county of Cook and State of Illinois, have invented a new, original, and ornamental Design for a Locking Device, of which the following is a specification, reference being had to the accompanying drawing, forming a part thereof.

In the drawing:

Fig. 1 is a perspective view of a locking device embodying my invention.

Fig. 2 is a top plan view of the locking device shown in Fig. 1.

Fig. 3 is a side elevation of the locking device shown in Fig. 1.

Fig. 4 is a bottom plan view of the locking device shown in Fig. 1.

I claim:

The ornamental design for a locking device, substantially as shown.

HARRY F. GEORGE.
